DESIGN FOR A STUFFED TOY OR SIMILAR ARTICLE

Jacob Swedlin, Brooklyn, N. Y.

Application September 16, 1941, Serial No. 103,373

Term of patent 7 years

To all whom it may concern:

Be it known that I, Jacob Swedlin, a citizen of the United States, residing in Brooklyn, in the county of Kings and State of New York, have invented a new, original, and ornamental Design for a Stuffed Toy or Similar Article, of which the following is a specification, reference being had to the accompanying drawings, forming a part thereof.

Fig. 1 is a front perspective view of a stuffed toy or similar article, showing my new design.

Fig. 2 is a side perspective view thereof.

I claim:

The ornamental design for a stuffed toy or similar article, substantially as shown.

JACOB SWEDLIN.
